GARMENT BAG

Joseph Hirsch Vineberg, Ottawa, Ontario,
Canada

Application May 31, 1943, Serial No. 489,220

2 Claims. (Cl. 206—7)

This invention relates to garment bags and particularly to those in which the garment is to be supported on a hanger.

According to present practice the garment is simply hung on a conventional hanger which is slipped into an open topped bag, the upper corners of the latter being folded over at an angle towards each other and secured in that position by some auxiliary means so that the bag will not slip off the hanger. Conventional hangers are expensive and the cheapest of them are, moreover, made of materials which in present circumstances are hard to obtain. Apart from this disadvantage from the retailer's point of view, the present arrangement is by no means entirely satisfactory from the customer's point of view. The folded corners must generally be secured in some permanent way, as by glue, because an easily removable fastening such as a pin might easily penetrate and mark the garment. Thus the bag can generally be removed only by tearing it and so destroying its utility for its intended purpose, namely, dust protection. Often, however, particularly in the case of garments not frequently worn, it would be advantageous to be able to replace the bag, as a dust cover, in the intervals between times when the garment is worn.

According to the present invention an arrangement is provided which avoids all these disadvantages both from the retailer's and customer's point of view. It permits the use of an inexpensive hanger of cardboard and the like, eliminates the necessity of an auxiliary securing means, and permits convenient removal of the garment from the bag without destruction of the latter. The garment bag according to the invention has longitudinal slits down its edges from its upper open end to provide two downwardly foldable portions. In these portions is formed a pair of opposed downwardly foldable flaps, while a similar pair of opposed upwardly foldable flaps of the same size as the downwardly foldable flaps is formed in the sides of the bag at a distance below the bottoms of the slits equal to the distance above these bottoms at which the downwardly foldable flaps are formed. A hanger member which may be of cardboard, heavy stiffened paper or the like, is adapted to fit in the bag and is composed of a hanger portion and a body portion with an opening through the body portion formed at substantially the same distance below the top of this portion as the distance below the bottoms of the slits at which the upwardly foldable flaps are formed, so that when the fold-

able portions are folded down into the bag all of the flaps and the opening register with each other and the flaps may be folded around the part of the body portion of the hanger above the opening to embrace that portion and hold the hanger in place. In this way an opening is left through the sides of the bag and the hanger which enables the hanger and bag to be grasped together, so that the bag is carried and the hanger is supported in position at the same time.

The invention will be described in more detail by reference to the attached drawing in which,

Figure 1 is a longitudinal section of a bag with a hanger of one type in position;

Figure 2 is a partial longitudinal section showing the preliminary folding operation;

Figure 3 is a longitudinal section showing the folding operations completed and the bag of Fig. 1 ready to carry;

Figure 4 is a perspective view of the type of hanger shown in Figures 1-3;

Figure 5 is a partial longitudinal view of a bag with a different form of hanger and part of the folding operations completed;

Figure 6 is a partial longitudinal section of the bag of Figure 5 with the folding operations complete, and

Figure 7 is a plan view of the bag of Figure 6 ready to carry.

The bag 10 in Figure 1 is the ordinary type of garment bag, made of light paper and closed at the bottom and open at the top. It is made slightly longer than normal and longitudinal slits 11 are cut down its edges from the upper open end to provide two downwardly foldable portions 12 and 13 at the top of the bag. In these portions are formed a pair of opposed flaps 14 and 15 which are connected to the main body of the portions 12 and 13 along their lower ends 14a and 15a, so that they are downwardly foldable. These flaps are shown in dotted lines in Figure 1 as slightly opened out, so as clearly to illustrate their position and relation to the portions 12 and 13 respectively. Below the bottoms 17 of the slits 11 a similar pair of opposed flaps 18 and 19 are formed in the sides 20 and 21 respectively of the bag, these flaps being connected to the sides along their upper ends 22 and 23 and being thus upwardly foldable. The flaps 18 and 19 are formed at the same distance below the bottoms 17 of the slits 11 as the flaps 14 and 15 are formed above these bottoms, the distance thus from the dotted line 24 to, for example, the lower end 14a of the flap 14 being equal to the distance from

the dotted line 24 to the upper end 22 of the flap 18.

Fitting within the bag 10 is a hanger member 25 which has an upper body portion 26 and a lower hanger portion 27. Formed in the body portion 26 is an opening 28 which is formed at substantially the same distance below the top 29 of the body portion as the distance below the bottoms 17 of the slits 11 at which the flaps 18 and 19 are formed. Thus it will be noted that the upper edge 30 of the opening 28 lies substantially in line with the upper edge 22 of the flap 18 when the upper edge 29 of the body portion of the hanger substantially coincides with the line 24. The opening 28 may be completely cut out or flaps which can be folded out of the way may be left in it.

The description thus far is applicable as well to the modification of Figures 1-4 as to the modification of Figures 5 and 6. It will be noted that in Figures 1-4 the hanger is formed of two thicknesses of material which are connected and folded one upon the other only along the lower edge 31 of the hanger portion 27. This construction enables the use of a comparatively thin stock for the hanger instead of the heavier cardboard which would otherwise be required, and the use of which is shown in Figure 5.

When the double thickness hanger is used, one half is held against one side and the other half against the other side of the bag. After the hanger with a garment hung on it has been inserted in the bag to the position shown in Figure 1, the foldable portions 12 and 13 are folded down to the position shown in Figure 2 and the flaps 14 and 15 are folded up through the openings 28a and 28b in the two sides of the hanger to lie between these sides of the hanger and the sides 20 and 21 of the bag, the position of the parts then being that shown in Figure 2. The final operation consists in folding the flaps 18 and 19 inward and upward so that they assume the position shown in Figure 3 and lie against each other on the one side and against the lower part of the foldable portions 12 and 13 respectively, on the other side. The position of the parts is then that shown in Figure 4, where it will be noted that a clear opening 32 is left through the bag and the hanger to provide a convenient hand grip. When the bag is carried by this hand grip the hanger is supported in the hand and there is very little strain on the bag itself.

In the arrangement of Figures 5 and 6 the preferred manner of holding the hanger in place

is slightly different. The flap 18 is folded up through the opening 28 to embrace the hanger. The foldable portions 12 and 13 are then folded inwardly, as in the case of Figure 2, and the flaps 14, 15 and 19 are then folded through the opening 28 in the order named, the final arrangement being that shown in Figure 6.

The arrangement described has all the advantages of the presently used bag and hanger combination at a minimum of cost. The bag can be hung up through the opening 32 in the same way as the present combination. If desired, the bag may be scored at the lower end, either all the way round so that the whole closed bottom may be removed or as shown in Figure 7 to form a tear strip 33. By removing the closed bottom of the bag or the tear strip along the scoreline, the customer may allow the lower part of the garment to hang freely from the hanger while at least partially covered by the bag for dust protection.

What I claim as my invention is:

1. A garment bag having longitudinal slits down the edges from the upper open end to provide two downwardly and inwardly foldable portions, a pair of opposed downwardly foldable flaps formed in said portions, a similar pair of opposed upwardly foldable flaps of the same size as said downwardly foldable flaps formed in the sides of said bag at a distance below the bottoms of said slits equal to the distance above said bottoms at which said downwardly foldable flaps are formed, a hanger member positioned between the inwardly foldable portions, said hanger member being composed of a hanger portion and a body portion having an opening therethrough of a size to receive said flaps, said hanger member fitting in said bag with the opening at substantially the same distance below the bottoms of said slits as the upwardly folding flaps, whereby when said foldable portions are folded down into the bag, all of said flaps and said opening will register with each other and said flaps may be folded around the upper part of the body portion of the hanger to embrace the same and hold the hanger in place.

2. A garment bag according to claim 1, in which the hanger is formed of two thicknesses of material connected and folded one upon the other only along the lower edge of the hanger portion, whereby the two thicknesses may be separately embraced by flaps formed in the two sides of the bag.

JOSEPH HIRSCH VINEBERG.
